(57) **CLAIM**

The ornamental design for a vehicle body as shown and described.

DESCRIPTION

FIG. 1 is a front perspective view of the vehicle body showing my design;

FIG. 2 is a front elevation view thereof;

FIG. 3 is a right-side view thereof;

FIG. 4 is a rear elevation view thereof; and,

FIG. 5 is a top plan view thereof.

The broken lines in the drawings are for the purpose of illustrating interior portions of the vehicle body and form no part of the claimed design.
